AUTOMOBILE SUN VISOR

Ernest F. Thomson, Tuckahoe, N. Y., assignor to
Casco Products Corporation, Bridgeport, Conn.,
a corporation of Connecticut

Application February 10, 1949, Serial No. 777

Term of patent 7 years

(Cl. D14—6)

To all whom it may concern:

Be it known that I, Ernest F. Thomson, a citizen of the Dominion of Canada (subject of the King of Great Britain), and residing at Tuckahoe, county of Westchester, and State of New York, have invented a new, original, and ornamental Design for an Automobile Sun Visor, of which the following is a specification, reference being had to the accompanying drawing, forming part thereof.

Figure 1 is a fragmentary perspective view of an automobile sun visor, showing my new design.

Fig. 2 is a perspective view of an automobile sun visor, showing my new design.

Fig. 3 is a fragmentary top or plan view of the visor shown in Fig. 1.

Fig. 4 is a sectional view taken along lines 4—4 of Fig. 3.

The underneath portion of the visor is entirely plain.

The characteristic features of my design reside in the parts shown in full lines in the drawing.

I claim:

The ornamental design for an automobile sun visor, substantially as shown and described.

ERNEST F. THOMSON.
